UNITED STATES PATENT OFFICE.

JOSIAH A. OSGOOD, OF BOSTON, MASSACHUSETTS.

PACKING FOR PISTON-RODS.

SPECIFICATION forming part of Letters Patent No. 274,365, dated March 20, 1883.

Application filed January 12, 1883. (No model.)

To all whom it may concern:

Be it known that I, JOSIAH A. OSGOOD, of Boston, county of Suffolk, State of Massachusetts, have invented an Improvement in 5 Packing for Piston-Rods, of which the following description, in connection with the accompanying drawings, is a specification, like letters on the drawings representing like parts.

My invention relates to a packing for piston-rods, valve-stems, &c., and has for its object to prevent the passage of water of condensation from a cylinder or steam-chest through the packing and along the piston-rod or valve-stem. In some kinds of engines—such, for instance, as steam-hammers—the escape of the water of condensation is a source of great inconvenience and even danger. For example, after a hammer has been standing still for a short time water will collect in the cylinder, 10 which, when the hammer is again to be set in operation, often passes through the packing and along the piston-rod, and in dropping upon the heated iron which is being operated upon by the hammer causes great annoyance 15 and even danger to the workman. The escape of water from a cylinder of the air-pump of an air-brake apparatus for railway trains is often troublesome, especially in cold weather, when it may freeze and thus interfere seriously with 20 the operation of the pump.

My present invention consists in the combination, with the usual packing or stuffing box and rod packed therein, of a water-removing device, such as hereinafter described, to remove the water from the said rod, and means 25 to convey the water thus removed to a place where it may be discharged without inconvenience or damage. The said water-removing device consists of one or more rings enclosing the rod and pressed against its sides, they accompanying the rod in its lateral vibrations relative to the packing-box or cylinder-head or other partition through which it passes, the said rings being connected with the stuffing or packing box in such a manner as not to 30 accompany the rod in its reciprocating movement. The said ring or rings thus operate to scrape the water from the sides of the rod, it being easier for the water to flow over the face 35 of the ring than between the ring and the rod. The water thus removed from the sides of the

rod is received in a chamber or reservoir, from which it may be led by a suitable pipe to any desired point.

The water-reservoir is shown in one instance 55 of my invention as consisting of an annular chamber surrounding and having an opening for the passage of the rod, of considerably greater diameter than the said rod, so as to permit the said lateral vibrations of the rod 60 without contact between it and the sides of the said reservoir, which is provided with a seat transverse to the said rod to receive the side of the water-removing rings surrounding the said rod and pressed closely against it 65 the said rings being dividedly transversely, and the portions pressed against the sides of the rod by a suitable spring. By this arrangement the water removing or scraping ring is held sufficiently close upon the rod to entirely 70 prevent the passage of water between it and the said rod, the said water being diverted over the outside of the said ring, from which it passes into the reservoir and is conveyed 75 away by a suitable eduction-pipe.

In another embodiment of my invention the water-receiving chamber is made in the scraping-ring itself, the bottom of the chamber being inclined so that the water flows toward one side thereof, from which it is discharged into 80 a receptacle provided with an eduction-pipe. This construction is especially convenient when the water-removing device is to be applied to an air-brake apparatus without altering its construction or taking it apart.

Figure 1 shows in longitudinal section a sufficient portion of a cylinder-head, packing-box, and piston-rod provided with a water-removing device for preventing the passage of water 85 of condensation along the rod in accordance with this invention, it being shown as applied to an air-brake apparatus; Fig. 2, a plan view of the water-removing ring detached; Fig. 3, a side elevation thereof; and Fig. 4 a vertical section of the apparatus, in which the annular water-receiving chamber is independent of the scraping-rings, which are inclosed in the said chamber and supported on a seat therein.

The piston rod *a*, and cylinder *b*, with its stuffing-box or packing *c*, may be of any usual construction, the said packing being herein shown as having a plane bearing, 2, and curved bear-

ing 3, to accommodate the lateral and angular deviation of the rod, the said packing, however, constituting no part of the present invention. At the outside of the opening in the 5 packing or stuffing box through which the rod *a* passes the said rod is provided with a water-removing device consisting of a ring, *d*, made in two portions, (shown in Fig. 3 as having portions *d'* overlapping one another so as to 10 break the joint between them, as best shown in Fig. 3,) one of the said portions being provided with a pin, *d''*, entering a socket in the overlapping part of the other portion of the ring, thus hinging the two together, they being 15 placed around the rod and pressed against its sides by a spring, *e*, (shown in Fig. 3 as a spiral spring,) resting in a groove in the lower portion of the ring, which is preferably of smaller diameter than the upper portion thereof. The ring is supported just at the end of 20 the packing-box, preferably by springs *f*, connected with the spring *e* and with eyes *h*, formed in a wire, *h'*, twisted around the stuffing-box, the whole thus being easily attached 25 without any alteration in the said stuffing-box. The ring pressed against the sides of the rod will scrape off or deflect the water issuing from the stuffing-box and flowing along the rod, the said water turning off over the surface of the 30 ring adjacent to the stuffing-box, and, as shown in Figs. 1, 2, and 3, the said ring is recessed or provided with a chamber, *i*, to receive the water thus removed from the rod. The bottom of the said chamber is inclined, it being lowest 35 adjacent to the point where the ends of the ring not connected by the pin *d''* meet and overlap, so that the water naturally flows toward this point, where it is discharged through the space 4, between the upper portion of the 40 two members of the ring. In order to convey the water thus discharged away from the stuffing-box *B* of the air-cylinder beneath, the said box *B* is provided with a receptacle, *k*, partially embracing the rod and fitted to the space 45 between the box *B* and ring *d*, and having feet *k'*, which enter the wrench-sockets 5 of the stuffing-box, or may be properly located to enter holes bored to receive them in the upper part of the stuffing-box *B*. The said receptacle is provided with an eduction-pipe, *m*, 50 by which the water is conveyed to any desired point, and the water thus collected at a single point flows away with sufficient rapidity not to freeze, as it would do if distributed in small drops over the surface of the box *B*. In the apparatus shown in Fig. 4 the chamber *i'*, which receives the water, is independent of the rings by which the water is removed 60 from the rod, the said chamber being connected with the stuffing-box by means of suitable lugs, *n*, and bolts or screws, and being annular in shape, as shown, its inner wall forming a passage through which the rod *a* passes, and being of sufficient size to accommodate 65 the lateral deviations of the said rod. The said inner wall is provided at its upper end

with a seat, *6*, to receive the scraping-rings *d'* *d''*, (shown as two in number,) each being divided to enable it to be placed around the rod *a*, and the two rings being so located as to 70 have the uncut portion of one opposed to the cut portion of the other to break the joint, in the usual manner. The said rings *d'* *d''* are shown as having their inner faces lined with soft or anti-friction metal *r*, and they are provided with grooves 7 at their periphery to receive springs *e'*, by which they are pressed tightly against the rod *a*, so as to prevent the passage of water between them and the said rod. A follower, *t*, is interposed between the 80 rings *d'* *d''* and the end of the stuffing-box or cylinder-head, as shown, it being provided with springs *u*, tending to press it against the said rings, and the latter upon the seat 6 on the reservoir *i'*. By this arrangement the rings 85 *d'* *d''* readily accompany the rod *a* in all its lateral movements, they then sliding on the seat 6, and thus always maintain a tight joint between their interior surfaces and the outer surfaces of the said rod, so that water passing 90 along the rod will be deflected over the tops of the said rings and will pass into reservoir *i'*, which is provided with an eduction-pipe, *m'*, by which the water is conveyed away to any desired point, it never accumulating to 95 any great extent in the said reservoir.

It will be seen that the efficiency of the herein-described device for removing water does not so much depend upon the absolute tightness of the joint between the rod and the 100 rings *d'* *d''* or between the latter and the reservoir *i'* as upon the fact that a much freer passage is afforded for the liquid over the outside of the rings and then away from the chamber than through the said joints, and that, although it is difficult to prevent the passage of the water from the cylinder by actual tightness of packing when pressure is brought to bear, the herein-described apparatus enables the said water to be conveyed away, so that 105 it will produce no inconvenience. The chamber surrounding the rod serves to receive the water from the sides of the rod and the rings and convey or guide it into the eduction-passage. 115

I claim—

1. In a packing for reciprocating rods, the combination, with a stuffing-box containing packing, of the water-removing ring outside of the said box, pressed against the sides of the rod and movable laterally therewith, and the chamber to receive and discharge the water collected from the rod, substantially as described. 120
2. The reservoir fixed relative to the rod and provided with a seat surrounding the said rod, combined with the water-removing ring held in close contact with the rod and movable laterally therewith upon the said seat, substantially as described. 125
3. The cylinder-head and stuffing-box containing packing, and the reservoir provided 130

with an outlet-passage, fixed thereon outside of the said box and surrounding the reciprocating rod, combined with water-removing rings held in contact with the said rod, and a 5 follower and springs whereby they are pressed against a seat in the said reservoir, as and for the purpose described.

In testimony whereof I have signed my name to this specification in the presence of two subscribing witnesses.

JOSIAH A. OSGOOD.
